AIR CLEANER

James Clark Evans, Detroit, Mich., assignor, by
mesne assignments, to King-Seeley Corpora-
tion, Ann Arbor, Mich., a corporation of Mich-
igan

Application March 2, 1936, Serial No. 66,525

7 Claims. (Cl. 183—15)

This invention relates to an air cleaner, and particularly to an air cleaner of the so-called oil bath type for use with internal combustion engines.

5 The invention is directed particularly to a cleaner of the type which has an outlet extending downwardly therefrom which adapts the cleaner for association with the so-called down draft carburetor, although the outlet tube may 10 be taken from the top of the cleaner. The cleaner comprises a sump for a cleansing liquid which is caught up by the moving air and separated therefrom, together with extraneous matter such as dirt and dust, by a filtering element. 15 In the passenger automobile of today, the space under the hood where the engine is located is at a premium, so that the size of the air cleaner is an important factor. However, in this type of cleaner, if the same is made too small the volume 20 of the filtering element will not be large enough to catch the oil, with the result that some oil may travel through the filter and on to the engine.

The present invention aims to provide a cleaner 25 which can be made on relatively small proportions and yet one in which this undesirable action will not occur. A further object of the invention is to provide a cleaner so constructed that the cleaning liquid or oil is caught up by air, even though the engine is operating at low or idling 30 speeds and the air velocity is low. Thus the air is efficiently washed even at low engine speeds. Also, in conjunction with this, it is an aim of the invention to provide a cleaner wherein there 35 will be no choking action on the engine and no oil gurgling noises at low engine speeds. A further object of the invention is to provide a cleaner of simplified construction embodying a minimum number of parts.

40 Fig. 1 is a vertical cross-sectional view taken through a cleaner constructed in accordance with the invention.

Fig. 2 is an elevational view of the cleaner of reduced size.

45 Fig. 3 is a detail view partly in section showing detailed structure.

Fig. 4 is a view showing the circular form of the cleaner partly in section and with parts broken away showing certain structural features.

50 Fig. 5 is a view looking into the lower casing member of the cleaner and showing the structure of a plate member.

A downwardly extending air inlet tube of a carburetor is shown at 1. The cleaner comprises 55 a casing advantageously of circular form in horizontal section, the same being illustrated generally at 2, having a circumferential side wall 3 and a bottom 4. Through the bottom extends an outlet tube 5, the lower end of which may be 60 slotted as at 6 and arranged to be fitted over the

top of and contracted upon the tube 1 by a clamp 7. The outlet pipe may have an internally extending bead 8 against which may rest a retaining ring 9 L-shaped in cross section, which holds a gasket 10 for sealing against the top of the pipe 1. The bottom 4 is flanged and welded to the outlet tube 5 as at 11. The top of the tube 5 may have a flange 12. A yoke 13 has arms suitably attached to the pipe 5 as by means of a weld, as shown at 14, and this yoke carries a screw 10 threaded stud 15 for receiving a winged nut 16.

The upper casing member comprises a top plate 20 and a member depending therefrom having a circumferential wall 21, the upper end of which is flared outwardly, with the top plate 18 and member 21 connected as at 22. This provides an annular air inlet 23 and an annular inlet passage 24. The lowermost end of the depending member is provided with a scalloped formation presenting alternating ridges and furrows 25 and 26. The member has a lower portion of spider formation, the same being cut out to provide bridging members of arms 27 extending radially inwardly to a central ring member 28. This provides a series of passageways 30. 25

There is a circular sleeve 31 fastened to the ring 28 as by means of welding and extends upwardly therefrom. Another spider member of cone formation has a number of arms or legs 32, the upper ends of which are suitably fastened, as by means of welding, to the top plate 20 as shown at 33. The lower and central portion of this spider member may be of solid formation, as shown at 34, and is secured to the upper end or sleeve 31, as at 35. The extreme inner end is 30 fashioned with a ledge 36 and depending part 37 for retaining a gasket 39 adapted to seat upon the flange 12. A filtering body 40 is carried by the upper member and this filtering body presents a mass with a multiplicity of interstices, as for example steel wool or the like. Preferably this mass is constituted by helical windings of irregularly shaped or corrugated wire or strip. When fashioned from such material the arms 27 and 32 amply support the same, as the wire or strip windings are capable of bridging the relatively wide openings 30 and the openings 41 between the arms 32. 35

A plate member generally indicated at 42 fits in the sump portion of the lower casing member 50 for which purpose the outer peripheral edge may be fashioned with a flange 43, the plate member having a horizontal portion spaced above the bottom 4, and a wall portion 44 rising therefrom and making substantial contact with the underside of the filter or legs 27. From the top of the wall 44 the plate has an inwardly extending part 45 which preferably extends inwardly and downwardly, and the plate has a central aperture 46 surrounding the tube 5 but of a larger diameter. 55

This plate divides the body of oil into a body thereabove which is in the path of air flow, and into a body therebelow which is out of the path of air flow. The edge 43 makes a good fit with 5 the casing wall to prevent air from passing through and into the body of oil below the plate.

The plate member also has oil flow apertures 47. At the crest of the bend line between the parts 44 and 45 the plate is provided with one 10 or more apertures 48 so that the oil level may rise in the space between the parts 44 and 45 as will presently appear. In the lower scalloped portion of the upper member, a number of apertures 50 are provided, preferably located in the portions 15 25. The metal extends inwardly from the scalloped portions to the arms 27 for strength purposes, as will be seen in Figs. 1 and 4. Oil may therefore collect in the channel at and just above the scalloped formation. This oil may drain back into the air passageway through the apertures 50.

The operation is as follows: The sump is to be filled with oil to the level substantially as indicated on Fig. 1, the oil sealing against the ridges 25 but leaving open passageways 51 at the location of the furrows 26. When the engine creates 25 a depression in the tube 5 air is drawn in through the passageway 24 and downwardly toward the oil sump. At moderate or high speeds the air is moving at such velocity as to whip the oil in the 30 passageway above the plate 42, entrapping some of the same and carry it into the filtering element. The plate 42 with its wall 44 defines the air passageway. The air moves downwardly then upwardly into the filter, as shown by the arrows. 35 Thus dust and dirt become wet with oil and the air cleansed thereby. The air velocity decreases in the filtering element, the oil is caught and entrapped therein with the clean air passing through the apertures 41, and thence into the 40 outlet pipe. The member 44 defines a quiescent zone leading back to the sump and to the oil underneath the plate 42. Thus the oil may flow, as indicated, over the portion 45 of the plate and back into the sump. As the oil is whipped out of 45 the passageway over the plate 42, the level of the oil in the quiescent zone is raised; and due to the vent-holes 48, the level of the oil may raise in the space between the wall 44 and part 45. This increased head causes oil to move upwardly 50 through the openings 41 into the air passageway. In this manner the oil has a complete circulation, and the sediment is largely deposited in the bottom of the sump 4. No oil is trapped in the filter, as all may flow therefrom through the apertures 55 50 opposite the quiescent zone.

The scalloped formation is designed to facilitate the cleansing of the air and efficient engine operation at low engine speeds or idling speed. At low speeds the rate of travel of the air may not 60 be sufficient to break the oil seal permanently, where, for example, there is a complete seal of the air passageway. This results in a choking action on the engine and an intermediate breaking of the seal, and a gurgling noise may become 65 audible. However, with the apertures 51 always open the air is directed therethrough in streams, with sufficient velocity to pick up and atomize some of the oil and carry it upwardly into the filtering element. Of course, at high speeds the 70 seal is well broken and most of the oil above the plate 42 has been displaced, with a resultant increase of head in the quiescent zone.

As above mentioned, space is at a premium in many cases, and one danger in making air cleaners of small dimension is that the oil will be 75

carried through the filter and on into the engine. To meet this situation, the partition of member 44 has been positioned to restrict the air flow channel and to restrict the area of the filter into which air carries the oil and to increase the quiescent zone. In other words, the rising member 44 is, in the present form, positioned so as to provide a generous quiescent zone or space between the tube 5 and the rising member 44. Thus, even though a large quantity of oil is in circulation 10 and much oil enters the filter, yet this oil easily escapes from the air stream, due to the large quiescent zone, and flows back into the sump; therefore, the height and size of the filtering element may be reduced, and yet oil will not be 15 drawn therethrough into the engine.

It will be noted that the member 45 extends inwardly and projects into the oil. This more or less seals off the quiescent zone so as to prevent air moving through the passageway 24 from 20 passing through the apertures 47, thence through the quiescent zone into the filtering element.

The term "oil" has been used herein when reference was made to the cleansing liquid. Oil is ordinarily employed for this purpose, though 25 other liquids may be used which may not technically be oil, and this term is intended to cover the same.

I claim:

1. An air cleaner comprising, a lower casing 30 member adapted to receive a quantity of oil with its lower portion constituting an oil sump, an upper casing member carrying a filtering body telescoped into the lower casing member in spaced relation to form an annular air inlet for the passage of air downwardly toward the sump and for the passage of air upwardly through the filtering medium, air outlet means connecting into the upper casing member above the filtering body, the filtering medium being above 40 the oil level in the sump, and a plate member having a laterally extending portion below the normal oil level and a rising wall portion extending upwardly and in substantial contact with the filtering medium to define an air passageway on one side and a quiescent zone on the other, said plate having an extending part projecting substantially from the top of the rising wall portion in a direction traversing the quiescent zone, with the free edge thereof projecting 50 below the normal oil level, said plate having apertures therein for the flow of oil from the lower portion of the sump into the air passageway.

2. An air cleaner comprising, a lower casing 55 member having an outlet tube extending through its bottom and adapted to receive a quantity of oil with its lower portion constituting an oil sump, an upper casing member carrying a filtering body telescoped into the lower casing 60 member in spaced relation to form an annular air inlet for the passage of air downwardly toward the sump and for the passage of air upwardly through the filtering medium, the upper casing member being in connection in its upper portion with the outlet tube, the filtering medium being above the oil level in the sump, and a plate surrounding the outlet tube having an outer laterally extending portion submerged in the oil and an intermediate upwardly rising wall 65 portion, the upper end of which makes substantial contact with the lower part of the filter, the said portion and rising wall defining an air passageway to the filtering body and the rising wall portion defining a quiescent zone in- 70 75

wardly thereof, the inner portion of said plate extending angularly inwardly and downwardly and terminating in an edge surrounding the outlet tube, and spaced therefrom, the laterally extending portion of said plate having apertures therein for the flow of oil from the lower portion of the sump into the air passageway.

3. An air cleaner comprising, a lower casing member having an outlet tube extending through its bottom and adapted to receive a quantity of oil with its lower portion constituting an oil sump, an upper casing member carrying a filtering body telescoped into the lower casing member in spaced relation to form an annular inlet for the passage of air downwardly toward the sump and for the passage of air upwardly through the filtering medium, the upper casing member being in connection in its upper portion with the outlet tube, the filtering medium being above the oil level in the sump, and a plate surrounding the outlet tube having an outer laterally extending portion submerged in the oil and an intermediate upwardly rising wall portion, the upper end of which makes substantial contact with the lower part of the filter, the said portion and rising wall defining an air passageway to the filtering body and the rising wall portion defining a quiescent zone inwardly thereof, the inner portion of said plate extending angularly inwardly and downwardly and terminating in an edge surrounding the outlet tube, and spaced therefrom and disposed below the normal liquid level, the laterally extending portion of said plate having apertures therein for the flow of oil from the lower portion of the sump into the air passageway.

4. An air cleaner comprising, a lower casing member having an outlet tube extending through its bottom and adapted to receive a quantity of oil with its lower portion constituting an oil sump, an upper casing member carrying a filtering body telescoped into the lower casing member in spaced relation to form an annular air inlet for the passage of air downwardly toward the sump and for the passage of air upwardly through the filtering medium, the upper casing member being in connection in its upper portion with the outlet tube, the filtering medium being above the oil level in the sump, and a plate surrounding the outlet tube having an outer laterally extending portion submerged in the oil and an intermediate upwardly rising wall portion, the upper end of which makes substantial contact with the lower part of the filter, the said portion and rising wall defining an air passageway to the filtering body and the rising wall portion defining a quiescent zone inwardly thereof, the inner portion of said plate extending angularly inwardly and downwardly and terminating in an edge surrounding the outlet tube and spaced therefrom and disposed below the normal liquid level, the laterally extending portion of said plate having apertures therein for the flow of oil from the lower portion of the sump into the air passageway, said plate having one or more vent apertures therein substantially at the top of the rising wall portion.

5. An air cleaner comprising, a lower casing member having an outlet tube extending through its bottom and adapted to receive a quantity of oil with its lower portion constituting an oil sump, an upper casing member carrying a filtering body telescoped into the lower casing member in spaced relation to form an annular air inlet for the passage of air downwardly toward the sump and for the passage of air upwardly through the filtering

medium, the upper casing member being connected in its upper portion to the outlet tube, the filtering body being above the oil level in the sump, and a plate surrounding the outlet tube having an outer laterally extending portion submerged in the oil and an intermediate upwardly rising wall portion, the upper end of which makes substantial contact with the lower part of the filter, the said portion and rising wall defining an air passageway to the filtering body and the rising wall portion defining a quiescent zone inwardly thereof, the inner portion of said plate extending angularly inwardly and downwardly and terminating in an edge surrounding the outlet tube and spaced therefrom and disposed below the normal liquid level, the laterally extending portion of said plate having apertures therein for the flow of oil from the lower portion of the sump into the air passageway, said upper casing member having a lower wall of scalloped or corrugated form, portions of which substantially seal with the oil at normal level and portions of which provide constantly open air passageways connecting the annular air inlet to the space below the filtering body.

6. In an air cleaner, a lower upwardly opening casing member adapted to receive oil and constituting an oil sump, an outlet tube extending through the bottom of the member, an upper casing member having inner and outer walls, a filtering body positioned between the walls, the said outer wall telescoping into and in spaced relation with the lower casing member to provide an air passageway downwardly toward the sump, the outlet tube connecting into the upper casing member above the filtering body, means for guiding air from the inlet passageway upwardly toward the filtering body and located in part below the normal oil level in the sump, said means directing the air to a portion only of the filtering body and defining a quiescent zone between the sump and another portion of the filtering body for the flow of oil from the filtering body back to the sump, means underlying and supporting the filtering body and forming, in conjunction with the outer wall of the upper casing, a channel formation, said upper casing member having apertures substantially in the channel formation for the flow of oil from the filtering body back into the air stream.

7. An air cleaner for internal combustion engines comprising, a lower casing member with a substantially centrally disposed outlet tube extending through the bottom thereof, said member being adapted to receive a quantity of oil and its lower portion constituting an oil sump, an upper member telescoping into the lower member in spaced relation to form an annular air inlet passageway, a filtering medium in the upper portion located substantially entirely above the oil, the outlet tube connecting into the upper portion above the filtering medium, said upper member having an annular wall extending downwardly into the lower member, the lower edge of said wall being substantially of scalloped or corrugated formation, with the ridges thereof substantially sealing with the oil when the same is at its normal level, and with furrows providing constantly open air passageways for the passage of air at low engine speeds, said scalloped formation having apertures therein substantially at the ridges for the flow of oil downwardly therethrough from the portion of the filtering medium lying thereabove.
